Attorneys.

UNITED STATES PATENT OFFICE.

ANTOINE A. LAURENT, OF MINNEAPOLIS, MINNESOTA.

HYPODERMIC SYRINGE.

Application filed February 17, 1927. Serial No. 168,932.

My invention relates to hypodermic syringes, and has for an object to provide a syringe which can be held and operated with great convenience, and which can be maintained filled with a supply of liquid to be injected hypodermically into the human body. The syringe is employed to inject liquid into the human body for the production of what is known as local anæsthesia, and may also be used for injecting serums and vaccines. It is essential for producing local anæsthesia to introduce relatively large quantities of the liquid into the area to be anæsthetized and it is, therefore, desirable that the syringe be so constructed that it can be refilled or kept in a filled condition without having to remove the hypodermic needle after the latter has been inserted. This invention is in the nature of an improvement on Patent No. 1,367,008 granted Feb. 1, 1921, to A. N. Bessesen and involves an improvement in connection with the valve construction and arrangement disclosed in said patent.

The full objects and advantages of my invention will appear in connection with the detailed description thereof, and the novel features of my inventive idea will be particularly pointed out in the claims.

In the accompanying drawings which illustrate a practical embodiment of my invention,

Fig. 1 is a view of the device partly in elevation and partly in central vertical section and showing the plunger moved inwardly. Fig. 2 is a view of the device in central vertical section showing the plunger moved outwardly. Fig. 3 is a view in section on the line 3—3 of Fig. 2.

Referring to the drawings for the purpose of describing the invention in detail, the syringe includes a cylindrical barrel 10 which at its forward end is threaded to receive a perforated cap 12. This cap is in turn threaded on its forward end to receive a hypodermic needle 14. The interior of the lower portion of the barrel 10 is provided with a valve seat 16 with which a forwardly opening check valve 18 is adapted to cooperate, the latter being normally held on the valve seat by a spring 20. The valve 18 is in the form of a ball to which is secured a stem 22 extending out through the passage in the cap 12 but smaller than this passage so as not to prevent the flow of liquid therethrough. The rear end of the

barrel 10 is provided with a screw cap 24 having two lateral diametrically opposite curved finger grips 26. Slidable in the barrel 10, there is a plunger 28 having a vertical screwthreaded opening into which the lower end of a hollow rod 30 is threaded. The longitudinal passageway 32 in this rod is closed at the bottom by a bolt 34 having a head 36 at one end and whose other end has a screwthreaded portion 38 which is screwed into the passage 32. The portion of the bolt between its head and screwthreaded portion extends loosely through a central opening in a plunger valve 40. The head 36 of the bolt is elongated as shown in Fig. 3 and fits into a circular recess in the bottom of the valve 40 so that the passage through the valve around the bolt is not obstructed. Inclined perforations 42 lead through the rod 30 and the plunger 28 beginning above the upper end of the bolt and passing through the lower surface of the plunger 28 about midway between its center and periphery. The contiguous surfaces of the plunger and plunger valve fit each other snugly when engaged so as to close the lower ends of the perforations 42 at such time. The hollow rod 46 passes snugly through a central opening in the cap 24 and at its upper end is threaded to receive an internally threaded boss 44 formed on a hand piece 46 shaped to receive the palm of the hand. The hand piece 46 contains a passageway 48 which communicates with the passageway 32 and also extends through a nipple 50 to which is attached a piece of rubber tubing 52 adapted to be connected with the source of liquid supply. The upper end of the plunger 28 has a sleeve portion 54 containing internal threads which receive the lower coils of a spring 56 whose upper end is anchored to a ring 58 held between the cap 24 and the upper end of the barrel 10.

In use, the hypodermic needle may be readily inserted wherever desired in the human body and with the fingers of the operator around the finger grips 26 and the palm of his hand upon the handpiece 46, pressure is exerted upon the plunger to cause the liquid below the latter to be forced through the needle into the part to be anæsthetized or into the part into which serum or vaccine is to be injected. At the same time, the spring 56 is stretched and the plunger valve 40 moves into engagement

with the lower surface of the plunger 28 thereby closing the passage through the perforations 42. Upon releasing the pressure of the hand, the spring retracts the plunger thereby producing a vacuum in the barrel below the plunger and causing liquid to flow from the source of supply into the vacuum chamber, the plunger valve then assuming the position shown in Fig. 2 so that there is a free passage for liquid through the perforations 42 and past the bolt 34. Upon starting to depress the plunger, the valve 40 immediately moves into position in engagement with the lower end of the plunger as shown in Fig. 1 so that back flow of liquid is prevented. There is a special utility for the stem 22 attached to the check valve 18 due to the fact that there is liability of this valve becoming stuck to its seat after the device has been in use. When such sticking occurs, the valve is readily released by pushing sidewise on the projecting end of the stem when the needle is detached. The extent of movement of the plunger valve relatively to the plunger may be varied by turning the screw bolt upwardly or downwardly as desired to effect the proper adjustment.

I claim:

1. In a hypodermic syringe having a barrel provided with an outlet opening containing an outwardly opening check valve, the combination of a plunger working in said barrel, a hollow rod attached at its inner end to said plunger, a plunger valve secured for limited movement with relation to the inner surface of said plunger, said rod and plunger containing inclined perforations passing through said rod and opening through said inner surface, and means for connecting the outer end of said rod with a source of liquid supply.

2. In a hypodermic syringe having a barrel provided with an outlet opening containing an outwardly opening check valve, the combination of a plunger working in said barrel, a hollow rod attached at its lower end to said plunger, a screw bolt hav-

ing its upper end screwed into the lower end of said rod, a plunger valve mounted on the lower portion of said bolt for limited movement thereon, said rod and plunger containing inclined perforations passing through said rod and opening through the lower surface of said plunger, and means for connecting the outer end of said rod with a source of liquid supply.

3. In a hypodermic syringe having a barrel provided with an outlet opening containing an outwardly opening check valve, the combination of a plunger working in said barrel, a hollow rod attached at its lower end to said plunger, a screw bolt having its upper end screwed into the lower end of said rod, a plunger valve containing an opening of larger size than said bolt, the latter passing through said opening whereby said plunger valve has a limited movement with relation to the lower surface of said plunger, said rod and plunger containing inclined perforations passing through said rod and opening through the lower surface of said plunger, and means for connecting the outer end of said rod with a source of liquid supply.

4. In a hypodermic syringe having a barrel provided with an outlet opening containing an outwardly opening check valve, the combination of a plunger working in said barrel, a hollow rod attached at its inner end to said plunger, a projecting stem secured to the lower end of said rod, a plunger valve having an opening therethrough of larger diameter than said stem for receiving the latter and permitting said valve to have a limited movement thereon, said rod and plunger containing inclined perforations passing through said rod and opening through the inner surface of said plunger, and means for connecting the outer end of said rod with a source of liquid supply.

In testimony whereof I hereunto affix my signature.

ANTOINE A. LAURENT.
